CLAIM

The ornamental design for a hair trimmer, as shown and described.

DESCRIPTION

FIG. 1 is a front, left and top perspective view of a hair trimmer, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of a portion of the hair trimmer shown in detail 9 in FIG. 1.

FIG. 10 is an enlarged view of a portion of the hair trimmer shown in detail 10 in FIG. 1.

FIG. 11 is an enlarged view of a portion of the hair trimmer shown in detail 11 in FIG. 2.

FIG. 12 is an enlarged view of a portion of the hair trimmer shown in detail 12 in FIG. 3.

FIG. 13 is an enlarged view of a portion of the hair trimmer shown in detail 13 in FIG. 7.

FIG. 14 is another front, left and top perspective view of the hair trimmer shown in an alternate configuration of use. The broken lines depict portions of the hair trimmer that form no part of the claimed design.

The dot-dash broken lines in FIGS. 1, 2, 3, 7, 9, 10, 11, 12 and 13 depict the boundaries of the enlargements that form no part of the claimed design.
